UNITED STATES PATENT OFFICE

117,860

DESIGN FOR A PROPELLER TYPE FAN

Walter L. Upson, Litchfield, Conn., assignor to
The Torrington Manufacturing Co., Torrington,
Conn., a corporation of Connecticut

Application January 20, 1939, Serial No. 82,451

Term of patent 14 years

To all whom it may concern:

Be it known that I, Walter L. Upson, a citizen of the United States, residing in the town of Litchfield, county of Litchfield, and State of Connecticut, have invented a new, original, and ornamental Design for a Propeller Type Fan, of which the following is a specification, reference being had to the accompanying drawing, forming a part thereof.

In the drawing:

Fig. 1 is a front elevational view of a propeller

type fan showing my new design, Fig. 2 is an enlarged sectional view as taken along line 2—2 of Fig. 1, and Fig. 3 is a side elevational view thereof.

The dominant feature of my design resides in the impressed portion on the center disc area of a one-piece fan.

I claim:

The ornamental design for a propeller type fan, substantially as shown and described.

WALTER L. UPSON.
